WELL PUMP

Thomas R. Alley, Houston, Tex.

Application May 24, 1946, Serial No. 672,146

8 Claims. (CL 103—46)

1

This invention relates to a well pump, and more particularly to pumps of the type that are operated by a pressure fluid conducted thereto from the surface.

An object of the invention is to provide a fluid operated pump that may be installed within, or removed from, a well by lowering or raising same within the well tubing.

Another object is to provide a pump of the class described of which the rate of operation is controlled by the rate of continuous admission of the operating fluid thereto.

Still another object is to provide a fluid actuated pump from which the pumped and operating fluids are exhausted through common ports.

The invention also comprehends the provision of a pump having a single valve element which controls both the admission and exhaust of the power fluid and the intake and discharge of the well fluids to the tubing string.

It is also an object to provide a pump which is so constructed as to prevent the backing up of well fluids into the power tubing and also to prevent well fluids in the flow string from draining back into the well when operation of the device is discontinued.

A still further object is to provide a well pump in which power is applied directly to the piston on the pumping stroke and the piston rod is therefore subjected to tension only.

Still another object is to provide a well pump having opposed pistons provided with valve rings movable by power fluid as the stroke is completed to move the control valve and thereby effect the reversal of travel of the piston assembly.

The foregoing together with other objects and advantages of the invention will be more fully apparent from the following description considered in connection with the accompanying drawings in which—

Fig. 1 is an elevational view partly in section showing the upper portion of one embodiment of the invention, this figure showing details of the unloading valve assembly;

Fig. 2 is an elevational view partly in section showing the pump unit located in the tubing string and is a continuation of Fig. 1;

Fig. 3 is a sectional view taken on line 3—3 in Fig. 1;

Figs. 4 to 6 inclusive are vertical sectional views through successive portions of the pump unit showing the parts in their relative positions for the beginning of the down stroke of the piston assembly;

Figs. 7 to 11 inclusive are transverse sectional

2

views taken on lines 7—7 to 11—11 in Figs. 4 to 6 inclusive, the direction of the respective sections of Figs. 4, 5 and 6 being indicated in the respective figures;

5 Figs. 12 to 14 inclusive are similar to Figs. 4 to 6 inclusive, but show the parts in the relative positions for the beginning of the up stroke of the piston assembly;

Figs. 15 to 17 inclusive are transverse sectional views taken on lines 15—15, 16—16 and 17—17 in Fig. 13, the orientation of these sections being indicated by the lines 13—13 in the respective figures.

Figs. 18 and 19 are schematic diagrams showing the complete layout of the pump and its flow passages and valves to facilitate an understanding of the invention. Fig. 18 shows the relative position of parts and directions of fluid flow at the beginning of, and during, the downstroke 10 while Fig. 19 shows these conditions at the beginning of, and during, the upstroke.

Referring first to Figs. 1 and 2 of the drawings, an embodiment of the invention is shown installed within a casing 1, the usual tubing 2 being suspended therein and having a special landing nipple 3 which comprises an element of a control valve assembly 4 to which is attached a power tubing 5 through which power fluid is transmitted to the pump unit 6. A shoe 7 at the lower end of the pump unit forms a seal 8 with the collar 9 at the lower end of the tubing string 2. It is intended that the seal 8 will be formed simultaneous with the formation of the seal 10 with the nipple 3 when the device is lowered to 30 pumping position at which time the head 11 of the control valve assembly lands upon the shoulder 12 in the nipple 3.

The chamber 13 between the casing 1 and the tubing 2 is utilized to conduct power fluid to the device, a packer 14 being set therebetween so that there is formed a chamber 15 below the chamber 13 and about the pump unit 6. While the packer 14 is usually used, it should be noticed that in some cases, particularly in shallow wells, the packer may be omitted and pressure fluid in the chamber 13 will, under such circumstances, be applied directly to the body of well liquid within the casing 1.

The control valve assembly 4 comprises the 40 landing nipple 3 having internal shoulder 12 to be engaged by a complementary outwardly extending shoulder on the head 11 which is shaped to be engaged by a releasable connector so that the entire pump assembly may be lowered into or withdrawn from the tubing 2. The head 11

is hollow and has ports 16 through which fluids pass as they move upwardly as indicated by the arrow 17. A packing mandrel 18 is threadedly connected to the lower end of the head 11 in a manner to provide a peripheral groove for the upper seal ring 10. This packing mandrel extends downwardly and is attached to the valve body 22 having depending skirt 21 which, together with ring 22 threaded thereon, forms a groove for the lower seal rings 23.

The valve body 20 has a passage 24 communicating with the annular space 25 about the mandrel 18 and thence through the passage 26 in the nipple 3 to the pressure fluid chamber 13. The passage 24 also extends both upwardly and downwardly in the valve body and the upper portion communicates with the small cage 27 in which there is a ball valve 28 adapted to seat within the upper end of the cage as indicated, or upon a seat at the upper end of the passage as indicated in dotted outline.

Alternately the ball valve may lift from its seat and effect aeration of fluids within the tubing 2 when pressures within and exteriorly of the tubing are substantially balanced. If these pressures are materially unbalanced the valve will, of course, seat as indicated in the drawing and hence pressure fluid entering through the passage 26 will be directed downwardly into the power tubing 5 and thence to the pump unit 6.

The unit 6 comprises a body made up of upper and lower tubular sections 31 and 32 interconnected at 33 whereby there are provided upper and lower cylinders 34 and 35 to receive the pistons 36 and 37 respectively. These pistons are secured to the ends of a piston rod 38 slideable within the sleeve valve 40 which is in turn slideable within the bore 41 intermediate the cylinders 34 and 35. It seems apparent that the piston 36 divides the cylinder 34 into upper and lower chambers 42 and 43 while the piston 37 similarly divides the cylinder 35 into upper and lower chambers 44 and 45.

The uppermost and lowermost chambers 42 and 45 are pumping chambers, while the intermediate chambers 43 and 44 are power chambers.

Power fluid admitted from the power tubing 5 enters a passage 50 which communicates alternately through port 51 of the sleeve valve 40, passages 52 and 53, and thence to chambers 43 and 44 as the valve 40 is reciprocated through a limited distance in the manner to be described. At the same time power fluid is alternately exhausted from the chambers 43 and 44 through passages 54 and 55, and to ports 56 and 57 of the valve 40 as they move into mating relation to complete these passages through exhaust outlets 58 and 59.

As the piston assembly is reciprocated by the power fluid in the manner just described, well fluid rises within the passage 60 to the port 61 in the valve 40 which port is in constant communication with the passage 60. When the valve 40 is in its lowermost position, as shown in Figs. 4, 5, 6 and 19, fluid is conducted through port 61 to passage 62 leading to the lower end of the chamber 45. Hence, as the piston assembly approaches its uppermost limit of travel, the chamber 45 is filled with well fluid being pumped. At the same time well fluid previously taken into the upper chamber 42 is being exhausted through passage 63 and port 56 in valve 40 to the exhaust outlet 58 which, as above pointed out, also

serves as an exhaust for power fluid on the succeeding stroke.

When the valve 40 is in its uppermost position as shown in Figs. 12, 13, 14 and 18, the port 56 of the valve has moved to communicate with passage 54 and outlet 58 to exhaust power fluid from chamber 43. Simultaneously the lowermost port 57 of the valve has moved to communicate with passage 66 to exhaust piped fluid through exhaust outlet 59. Port 61 has moved into mating relation with passage 60 and thereby communicates with passage 67 whereby well fluids are admitted to chamber 42 to be exhausted therefrom on the succeeding stroke.

It is to be noted that each of the pistons 36 and 37 has a skirt portion within which is slidably fitted a valve ring 70 which also fits closely about the piston rod 38. These valve rings are retained within the pistons by means of stop rings 71 and in this manner the valve rings are mounted for limited travel within the pistons.

The piston rod 38 has a longitudinal bore 72 which terminates in ports 73 within the pistons and inwardly of the valve rings 70. A radial passage or port 74 in the piston rod is normally closed as the rod moves within the sleeve valve 40. As the pistons approach the ends of their strokes this port is opened and pressure fluid is thereby admitted to the bore 72 whereby pressure is exerted upon the rings to move toward the innermost ends of the pistons. The ring on the innermost piston engages the end of the sleeve valve 40 and moves the valve to a new position, thereby covering the port 74 and initiating the succeeding stroke. When the port 74 is again uncovered at the opposite end of the stroke, this cycle is again repeated and in this manner the continuous pumping operation is effected.

Positioned upon the upper portion of the valve 40 is a grooved port 80 which communicates with the exterior of the pump body by means of radial passageway 81. This arrangement serves to release pressure from above the valve ring 70 in the upper piston 36 and below the companion ring in the lower piston 37 through the passageway 72 when port 74 passes the grooved port 80 on the down stroke of the piston rod 38. Likewise a grooved port 80' together with the radial port 81' serves to release pressure from the above indicated areas upon the upward stroke of the piston rod 38. Passageways 81 and 81' being of relatively small diameter, further serve to cushion the action of the valve 40 as it is moved in each direction.

Substantially midway between the ports just indicated there is the grooved interior port 82 in the valve 40, which port is connected by means of passage 83 with the well liquid intake port 60. The grooved port and passage serve to conduct a lubricating fluid to the surface of the sleeve valve 40.

The pumped and power fluids exhausted from exhaust ports 58 and 29 rise as indicated by the arrows 75 and pass upwardly through the openings 76 in the valve body 20 to be exhausted from the tubing 2 at the surface.

Power fluid admitted from the power tubing 5 enters a passage 50 which communicates alternately through passages 52 and 53 with the inner chambers 43 and 44 of the cylinders as the port 51 of the sleeve valve 40 moves to and from mating relation with the respective passages. As these ports move from such mating relation they form a communication with exhaust out-

lets 54 and 55 and in this manner the valve ports serve as both inlet and exhaust ports for the pressure fluid which is ultimately exhausted into the annular space about the pump body.

The operation of the device of the invention is believed apparent from the foregoing description. By way of summary it will be assumed that the tubing string 2, together with nipple 3 and the extension of the tubing string therebelow are already in place within a well. As previously indicated the packer 14 may be installed, although in some cases this packer may be omitted.

The entire control valve assembly 4 and the pump unit 6 are interconnected by means of the power tubing 5 and this assembly is lowered within the tubing 2, preferably upon a wire line although it is apparent that the unit could be lowered by means of a fluid pumped downwardly through the tubing 2.

When the control valve and pump unit assembly has landed in place upon the shoulder 12 and the respective seals are formed with the surrounding tubing, the complete assembly is ready for operation.

Pressure fluid is then introduced to the annular chamber 13 from the mouth of the well and such fluid is admitted through the passageway 26 to the interior of the valve assembly 4. If the pressure within the tubing 2 and that within the annular chamber 13 are substantially equal, a slight increase in pressure in the latter chamber will cause the ball valve 28 to rise and thereby to admit pressure fluid which aerates the column within the tubing 2. Such operation may continue until a portion of the fluid is ejected from the well or until such differential pressure has developed that the valve 28 engages its upper seat. Thereupon continued application of pressure fluid within the chamber 13 moves downwardly through the power tubing 5 whence it is admitted through the passage 50 in the pump body and the port 51 in the valve 40 alternately to the upper and lower pressure chambers 43 and 44.

At the same time well fluid is admitted through the passage 60 to port 61 whence it is alternately directed through passages 62 and 67 to the lower and upper pumping chambers 45 and 42 respectively.

Particular attention is directed to the fact that at any instant the pumping piston is actuated by pressure applied to the opposite side thereof, and hence the force necessary to effect pumping is not transmitted through the piston rod 38. For this reason the piston rod is subjected to tension only and the possibility of failure thereof or the necessity of providing a massive piston rod structure are avoided.

It is understood of course that, as above explained, pressure fluid in the power chambers 43 and 44 is admitted through port 74 in the piston rod to actuate valve rings 70 in proper sequence that the sleeve valve 40 is moved at the end of each stroke to effect the operational steps to which reference has just been made.

Broadly the invention comprehends a well pump of the pressure fluid operated type that is simple in construction, easy to install, and efficient in its operation.

The invention claimed is:

1. A well flowing device comprising, a tubing string, a control valve assembly therein having spaced seals with the surrounding tubing, there being an opening to admit pressure fluid about

the assembly intermediate said seals from the exterior of the tubing string, fluid operable pump means below said assembly, a power string connecting the assembly to said means there being constant communication between said opening and said power string, and additional means in said assembly responsive to an excess of pressure from within the tubing string for admitting the pressure fluid directly to said string.

10 2. In a well flowing device, a control valve assembly including a valve body, there being a passage from the exterior or to the interior of the body for the admission of a pressure fluid and said passage having upwardly and downwardly extending portions, a valve cage surrounding the upwardly extending portion of the passage, opposed valve seats in said cage, a valve within the cage movable to engage either of said seats and to a position intermediate thereof whereby an excess of pressure above the valve permits unseating from the upper seat and aeration of fluid thereabove, a fluid pressure actuated pumping unit below said assembly, and a power tubing connecting the downwardly extending portion 25 of the passage to the unit and in constant communication with said passage.

30 3. In a fluid operated well pump, a body having spaced cylinders therein, a piston slidably mounted in each of said cylinders, a piston rod interconnecting said pistons, a sleeve valve slidably within the body between said cylinders, there being cooperating passages in said body and ports in said valve for alternately admitting well fluids to and exhausting such fluids from the cylinders 35 outwardly from the pistons, and valve means in each of said pistons responsive to fluid pressure for alternately moving said sleeve valve and admitting power fluid to the respective pistons as they successively complete the intake stroke.

40 4. In a fluid operated well pump, a body having spaced cylinders therein, a piston slidably mounted in each of said cylinders, a piston rod interconnecting said pistons, a sleeve valve slidably within the body between said cylinders, there being cooperating passages in said body and ports in said valve for alternately admitting well fluids to and exhausting such fluids from the cylinders outwardly from the pistons, a valve ring in each of said pistons, and means for moving the valve 45 50 ring to actuate the sleeve valve as the pistons approach the end of their stroke.

55 5. In a fluid operated well pump, a pump body, spaced aligned cylinders therein, pistons in said cylinders forming an inner and an outer chamber in each cylinder, a piston rod connecting said pistons, said piston rod having a passage therein terminating within ports interiorly of the pistons, a sleeve valve slidably axially of the body intermediate said cylinders, said piston rod passing slidably through said valve, there being an additional port in said rod normally closed by said valve but adapted to be uncovered as the pistons move to terminal positions, and a valve ring in each of said pistons operable by power fluid admitted 60 through said additional port for moving the valve and reversing the stroke, and cooperating passages in the body and ports in the valve for alternately admitting power fluid to and exhausting power fluid from the chamber below the upper 65 piston on the upward stroke and the chamber above the lower piston on the downward stroke.

70 6. In a fluid operated well pump, a body having spaced cylinders therein, a piston slidably mounted in each of said cylinders, a piston rod interconnecting said pistons and having a passage lon-

gitudinally thereof and terminating proximate said pistons, a valve slidable within the body between said cylinders, there being cooperating passages in said body and ports in said valve for alternately admitting well fluids to and exhausting such fluids from the cylinders outwardly from the pistons, and fluid actuated valve means in each of said pistons operable by pressure fluid admitted through the passage in the piston rod for alternately moving said first mentioned valve and admitting power fluid to the respective pistons as they successively complete the intake stroke.

7. In a fluid operated well pump, a body having spaced cylinders therein, a piston slidably mounted in each of said cylinders, a piston rod interconnecting said pistons and having a passage longitudinally thereof and terminating proximate said pistons, a valve slidable within the body between said cylinders, there being cooperating passages in said body and ports in said valve for alternately admitting well fluids to and exhausting such fluids from the cylinders outwardly from the pistons and for alternately admitting power fluid to the opposite sides of such pistons to effect reciprocation thereof, and fluid actuated valve means in each of said pistons operable by pressure fluid admitted through the passage in the piston rod for alternately moving said first mentioned valve and admitting power fluid to the respective pistons as they successively complete the intake stroke.

8. In a fluid operated well pump, a body having

spaced cylinders therein, a piston slidably mounted in each of said cylinders, a piston rod interconnecting said pistons and having a passage longitudinally thereof and terminating proximate said pistons, a valve slidable within the body between said cylinders, there being cooperating passages in said body and ports in said valve for alternately admitting well fluids to and exhausting such fluids from the cylinders at one side of each of said pistons and for alternately admitting power fluid to the other side of each of said pistons to effect reciprocation thereof, and fluid actuated valve means in each of said pistons operable by pressure fluid admitted through the passage in the piston rod for alternately moving said first mentioned valve and admitting the power fluid to the respective pistons as they successively complete the intake stroke.
